UNITED STATES PATENT OFFICE.

CROMWELL A. B. HALVORSON, JR., OF SAUGUS, MASSACHUSETTS, ASSIGNOR TO
GENERAL ELECTRIC COMPANY, A CORPORATION OF NEW YORK.

INCLOSED-ARC LAMP.

1,132,259.

Specification of Letters Patent.

Patented Mar. 16, 1915.

Application filed June 30, 1913. Serial No. 776,468.

To all whom it may concern:

Be it known that I, CROMWELL A. B. HALVORSON, Jr., a citizen of the United States, residing at Saugus, in the county of 5 Essex, State of Massachusetts, have invented certain new and useful Improvements in Inclosed-Arc Lamps, of which the following is a specification.

My invention has reference to an inclosed 10 arc lamp, and more particularly to a lamp of this character which is adapted to use flaming electrodes from which solidifiable products of combustion are evolved and which when they are deposited on the globe 15 obscure the light and decrease the efficiency of the lamp.

My invention provides a novel form of 20 arc inclosure in which the gases evolved from the arc are first caused to circulate in a part of the inclosure above the globe where the solidifiable products are caused to deposit, so that when the gases are returned to the globe, they are so far freed from 25 solidifiable products of combustion that the globe remains substantially free from deposit.

For a fuller understanding of my invention reference may be had to the accompanying drawings in which—

30 Figure 1 is a vertical section of a lamp embodying my invention; Fig. 2 is a bottom plan view of the same on an enlarged scale with the globe removed, and Fig. 3 is a modification.

35 In the drawings, 1 is the canopy of the lamp which is supported by the usual insulated hook 2. The bottom of the hood is closed by a plate 3. Two tubes 4 and 4' are received within openings in the plate 3 and 40 communicate with the chamber formed by the hood, and thus communicate with each other at their upper ends. A bottom plate 5 is suitably secured to the lower ends of the tubes 4. A drum 6 is secured to the outer 45 edge of the bottom plate 5 and is provided at its lower edge with an inwardly extending flange 6^a. A suitable globe seat 7 in the form of an annular ring is secured to the flange 6^a and the globe 8 is seated against 50 the plate 7. In the preferred form of my lamp a cylindrical partition plate 9 is located within the drum and is of substantially the same height as the drum, one side of the cylinder being internally tangential 55 to one side of the drum 6 and the other side

of the cylinder being located between the lower ends of the tubes 4 and 4' so as to form a partition in the drum between the tubes and so that one of the tubes 4 will communicate with the globe through the cylindrical member 9, while the other tube 4' communicates with the globe through the space between the drum and the inner cylinder. The upper and lower electrodes are indicated by the reference numerals 10 and 11. The upper electrode is received within a suitable carbon-holder 12 and passes through a gas cap 13 secured to the top plate 9, while the lower electrode 11 is received within a carbon-holder 14 supported by the carbon carrying rod 15 (Fig. 2). The upper electrode passes through an economizer 16 which is provided with an upwardly extending cylindrical member 17 secured to the bottom plate 5 of the lamp. 75 The cylinder 17 is somewhat wider than is necessary to receive the upper electrode so as to form a gas pocket which prevents consumption of the upper electrode above the arc. A cylindrical member 18 surrounds the 80 gas cap 13 and extends above the same to form a support for the operating mechanism.

In operation the fumes evolved from the arc ascend, and experience has shown that 85 the ascent is biased toward and through the cylindrical member 9, into the tube 4 communicating therewith; the fumes then pass through the chamber formed by the hood 1 and plate 3 through the tube 4', through 90 which the gases descend and enter the globe through the space formed between the drum 6 and the cylindrical member 9. During this circulation, the solidifiable products of combustion in the gases are mostly deposited within the tubes and in the depositing 95 chambers formed by the hood and by the drum 6, and the gases are thus relieved of such products of combustion so that when they are returned to the globe, little, if any, 100 deposit takes place on the portion of the globe through which the light passes.

I have not illustrated the arc lamp mechanism, as this constitutes no part of my present invention and any well known mechanism for starting and regulating the arc and feeding the electrodes may be employed, though I prefer a mechanism which feeds both electrodes together in such a way that the arc is focused.

It will be seen that my lamp utilizes the hood of the lamp as a part of the circulatory system for the fumes, and that the structure of the circulatory system is extremely simple; the same has been found, in actual operation to be efficient.

While the arrangement shown in Figs. 1 and 2, is preferred on account of the finished aspect which it gives to the lamp, I 10 have found that I may dispense with the upper condensing chamber by joining the tubes 4 and 4' at their upper ends by a curved pipe 1', as shown in Fig. 3, and which in this case takes the place of the 15 ordinary hood.

What I claim as new and desire to secure by Letters Patent of the United States, is:—

1. In an arc lamp, a substantially airtight arc inclosure comprising a transparent 20 or translucent globe surrounding the arc surmounted by a fume receiving and condensing drum freely communicating with the top of the globe, and two metallic tubes communicating with the top of the drum 25 and with each other at their upper ends, and

a partition mounted within said drum between the two tubes.

2. In an arc lamp, upper and lower electrodes, a substantially air tight arc inclosure comprising a transparent or translucent 30 globe surrounding the arc surmounted by a drum and two metallic tubes communicating with the top of said drum and a closed hood for the lamp forming a depositing chamber mounted upon the tops of said 35 tubes and communicating therewith, and a cylinder of less diameter than the drum mounted eccentrically within the drum so as to partition the space within the same, one of the tubes communicating with the globe 40 through the cylinder and the other through the space between the drum and the cylinder, and the upper electrode extending within said cylinder.

In witness whereof, I have hereunto set 45 my hand this 27th day of June, 1913.

CROMWELL A. B. HALVORSON, JR.
